UNITED STATES PATENT OFFICE

HENRY C. McCLOSKEY, OF WICHITA FALLS, TEXAS

CONVERTIBLE TABLE AND VALISE

Application filed April 3, 1928. Serial No. 267,106.

The invention provides an article particularly adapted for picnickers and tourists since it may be readily adjusted for use as a table and easily and quickly reduced to a compact form for convenience of handling and storage and receiving sundry articles adapted to be packed into a valise or analogous container.

The invention relates to an article of the nature aforesaid which in either adjustment presents storage compartments, or receptacles, in which tableware, food, dishes and the like may be placed and which are readily accessible at all times, whether the device is set up for use as a table or reduced to the form of a valise.

The invention provides a convertible article of the character stated which is light, durable and capable of being manipulated with ease and dispatch when converting it from one use to another, and which is portable and compact to occupy a small space for carrying and transporting.

While the drawings illustrate a preferred embodiment of the invention, it is to be understood that in adapting the means to meet specific needs and requirements, the design may be varied and such other changes in the minor details of construction may be resorted to within the scope of the invention as claimed, without departing from the spirit thereof.

For a full understanding of the invention and the merits thereof reference is to be had to the following description and the drawings hereto attached, in which:

Figure 1 is a perspective view showing the device reduced to the form of a valise.

Figure 2 is a perspective view showing the device adjusted for use as a table.

Figure 3 is a view of the device in the form of a table and inverted, the legs being in section, parts broken away and a section of the top being partly drawn out.

Figure 4 is a section on the line 4—4 of Figure 3, looking in the direction of the arrows.

Figure 5 is a sectional view on the line 5—5 of Figure 3, looking in the direction of the arrows.

Figure 6 is a sectional view on the line 6—6 of Figure 3, looking in the direction indicated by the arrows, the legs being in full.

Corresponding and like parts are referred to in the following description and designated in the several views of the drawings by like reference characters.

The device comprises similar sections or parts which are hingedly connected and provided with folding legs. Each of the sections includes a frame, a top, a storage compartment, a leg receiving compartment, and closures for the top and bottom of the compartments, whereby access to the storage compartment may be readily had when the device is adjusted for use as a table or valise, and is set upon its legs, or inverted and resting upon its top, as indicated in Figure 3 of the drawings.

Each of the frames includes an outer longitudinal rail 1, an inner longitudinal rail 2, and end rails 3. An intermediate longitudinal rail 4 is spaced a short distance from the outer rail 1 and is connected at its ends to the rails 3. The compartment or space 5 thus formed between the longitudinal rails 1 and 4 receives the legs 6 which are adapted to fold therein. The legs 6 are hinged to the top, as indicated at 7, and are held extended by flat springs 8 set into recesses formed in the sides of the rails 4 and made fast at one end to the said rails and free at the opposite end to engage a side of the legs and hold them when swung outward into operative position. The legs at each side fold one upon the other, as indicated in Figure 6. Fillers 9 are disposed between the ends of the rails 2 and 4 against the end rails 3 and are secured thereto. Hinges 10 connect these fillers and the sections comprising the device.

The space enclosed by the rails 2 and 4 and the fillers 9 constitutes a compartment 11 in which tableware, food, and sundry articles are adapted to be stored. This storage compartment is open at the top and bottom and is normally closed by covers which are movable to admit of ready access to the compartment from either the top or the bottom as required. The upper closure forms part of the table top and the outer sides of the valise. This

closure includes a medial section 12 and end sections 13. The end sections 13 are fixed. The medial section 12 is slideable in and out. The meeting edges of the sections are halved 5 as indicated most clearly in Figures 4 and 6 of the drawings. The top closure extends over both compartments 5 and 11. A longitudinal strip 14 secured to the bottom side of the section 12 forms a stop to limit its sliding movements in both directions. The ends 10 of the stop strip 14 project beyond the sides of the section 12 and underlap the end sections 13 and rest upon transverse strips 15 extending between the rails 2 and 4 and spaced 15 from the end sections 13 a distance to snugly accommodate the ends of the stop 14. The strips 15 provide rests which assist materially in retaining the sliding top sections 12 in position during their sliding movements. 20 The bottom closure 16 is hinged to the rail 2 as indicated at 17, and is retained in closed position by suitable fastening means 18.

When the device is folded into compact form it presents the appearance of a valise, 25 as shown in Figure 1 of the drawings. It is provided with handles 19 and fastenings 20. Access is readily had to either one of the storage compartments 11 by sliding the section 12 outwardly as will be readily appreciated. 30

When the device is set up for use as a table, the complementary sections are opened out 35 flat and the legs 6 are extended. Access to the storage compartments 11 is had by sliding the sections 12 laterally, as indicated in Figure 3, or by opening the closures 16. It makes no difference whether the table is set upon its legs, as shown in Figure 2, or inverted and placed upon its top, as illustrated in 40 Figure 3, access may be readily had to either one of the storage compartments.

Having thus described the invention, I claim:

A convertible table and valise comprising 45 sections, each section including an inner, an outer, and an intermediate longitudinal rail and end connecting rails, fillers between the ends of the inner and intermediate longitudinal rails, hinges connecting the fillers, legs 50 foldable in the spaces formed between the outer and intermediate longitudinal rails, flat springs for holding the legs extended applied to one of the longitudinal rails, a hinged bottom for each of the sections, a top for each 55 section comprising fixed end members and an intermediate sliding member, transverse strips between the fixed end members, and a longitudinal strip carried by the sliding member and coacting with the fixed end members 60 and the transverse strips to retain the sliding member in place and limit its movements.

In testimony whereof I affix my signature.
HENRY C. McCLOSKEY. [L. S.]
